DESIGN FOR A FAUCET

Otto G. Hitchcock, Erie, Pa., assignor to Hays
Manufacturing Co., a corporation of Pennsyl-
vania

Application December 7, 1934, Serial No. 54,326

Term of patent 14 years

To all whom it may concern:

Be it known that I, Otto G. Hitchcock, a citizen of the United States, residing at Erie, in the county of Erie and State of Pennsylvania, have invented a new, original, and ornamental Design for Faucets, of which the following is a specification, reference being had to the accompanying drawing, constituting a part hereof.

Fig. 1 is a top plan view of the faucet, showing my new design;

Fig. 2 is a front elevational view of the faucet shown in Fig. 1; and

Fig. 3 is a side elevational view of the faucet shown in Fig. 1.

I claim:

The ornamental design for a faucet substantially as shown.

In testimony whereof I affix my signature.

OTTO G. HITCHCOCK.
